COMBINATION HOT LATHER DISPENSER AND AEROSOL LATHER CONTAINER

Theodore R. Flowers, Fairfield, Conn., assignor to Eversharp, Inc., a corporation of Delaware

Filed Nov. 15, 1967, Ser. No. 9,413

Term of patent 14 years

Int. Cl. D6—01

U.S. Cl. D33—30

FIG. 1 is a perspective view of a combination hot lather dispenser and aerosol lather container showing my new design;

FIG. 2 is a side elevational view thereof;

FIG. 3 is a front elevational view thereof;

FIG. 4 is a rear elevational view thereof;

FIG. 5 is a top plan view thereof; and

FIG. 6 is a bottom plan view thereof.

I claim:

The ornamental design for a combination hot lather dispenser, and aerosol lather container, as shown.
